UNITED STATES PATENT OFFICE.

RALPH H. SMITH, OF BROOKLYN, NEW YORK.

EXTENSION ARM FOR PULLEY LINES.

Application filed February 4, 1924. Serial No. 690,597.

To all whom it may concern:

Be it known that I, RALPH H. SMITH, a citizen of Canada, having taken out first United States citizenship papers, and a resident of the city of New York, borough of Brooklyn, in the county of Kings and State of New York, have invented a new and Improved Extension Arm for Pulley Lines, of which the following is a full, clear, and exact description.

This invention relates to an extension arm for pulley lines and has for an object to provide an improved construction which may be readily swung in through a window when the same is open and again to a position outside of the window when it is desired to close the window.

Another object of the invention is to provide a support for a pulley line which may be mounted on the outside of a window and which may be swung substantially horizontally through the window at any time with the line maintained substantially taut when extending through the window or when positioned exteriorly thereof.

A further object, more specifically, is to provide an arm for pulley lines and a support therefore which will substantially lock the arm in either an inner or outer position and which will maintain the line under tension at all times.

In the accompanying drawing—

Figure 1 is a horizontal sectional view through a window with an embodiment of the invention applied thereto.

Figure 2 is a perspective view of one end of the arm shown in Figure 1 and a supporting bracket for mounting the arm in position.

Figure 3 is a detail fragmentary perspective view showing a slightly modified form of arm to that illustrated in Figure 1.

Referring to the accompanying drawing by numerals, 1 indicates the window frame which is provided with the usual sill 2. When the frame 1 is not of the proper size or shape, a block 3 may be secured thereto of any desired size and shape in order that the bracket 4 may be connected thereto as well as to the window frame 1. The bracket 4 carries an arm 5 which at its outer end is supplied with a hook 6 for receiving the pulley 7, said pulley in turn receiving the line 8. The bracket 4, as more clearly shown in Figure 2, is provided with a pair of upstanding ears 9 at the inner end, a pair of com-

paratively small ears 10 near the outer end and a pair of hook members 11 at the extreme outer end. The bracket 4 is also provided with a depression 12 whereby a shoulder 13 is formed. This shoulder is designed to receive the corner 14 of the inner end of arm 5 when the arm 5 is moved to the dotted position shown in Figure 1. The arm 5 is pivotally mounted on the ears 10 by a suitable pivotal pin or bolt 15 and the arm is thereby permitted to swing back and forth for about a quarter of a circle. The ears 9 are provided with suitable apertures for receiving a pin 16 which may be readily removed at any time, said pin acting to temporarily lock the arm 5 in its inner position as shown in Figure 1 whereby clothes may be placed on the line 8 without the operator hanging out the window.

After the clothes have been placed on the line, the two runs of the line are passed over one of the hook members 11 as shown in dotted lines in Figure 1 and then the pin 16 removed. The arm 5 and associated parts are then swung outwardly until the corner 14 engages the shoulder 13 as indicated in dotted lines in Figure 1, after which the pin 16 is replaced in order not to mislay the same. The window sash may then be lowered and the window completely closed.

When it is desired to remove the clothes from the line 8, the window sash is opened and the parts moved back to the position shown in Figure 1.

In Figure 3 will be seen a slightly modified form of arm wherein a sliding or telescoping section 17 is fitted over the arm 5 and is locked in any desired adjusted position by suitable means, as for instance, a set screw 18. When using this construction, the arm may be lengthened to any desired extent within the limits of the length of arm 5 and section 17 whereby the clothes may be hung on the line wholly within the house.

What I claim is:

1. A clothesline support, comprising a swinging arm, means for supporting the swinging arm in an inner and an outer position, said means comprising a bracket adapted to be mounted on the window frame, said bracket being provided with a shoulder for limiting the swinging movement of the arm in one direction, a pair of spaced ears near one end, a pair of spaced ears near the other end, a pivot pin extending through the second mentioned ears and through said

arm near one end for pivotally mounting the arm on said bracket, said arm being adapted to extend between the first mentioned pair of ears when the arm is in an inner position, said bracket being also provided with a pair of facing hook members outside of and near the ears carrying said pivot pin, a removable pin extending through the first mentioned pair of ears for locking said arm in an inner position, said arm being adapted to be swung until one end engages said shoulder when said removable pin is removed, means carried by the free end of said arm for receiving a clothesline, said pivot pin being positioned outside of said shoulder whereby when the end of the arm opposite the free end is against said

shoulder the clothesline may be looped over one of said facing hooks and the pull of said clothesline on the free end of said arm will cause the opposite end of the arm to press against said shoulder.

2. In a clothesline support, a bracket for supporting an arm, said bracket being formed with a base having a pair of spaced ears at one end, said ears being apertured for receiving a pin, a pair of spaced ears near the opposite end formed with apertures for receiving a pivotal pin, a pair of hooks arranged near the last mentioned ears, and a shoulder arranged in the base adjacent the second mentioned ears.

RALPH H. SMITH.
